(57) **CLAIM**

I claim the ornamental design for a game console, as shown and described.

DESCRIPTION

FIG. 1 is a perspective view of a game console showing my new design;

FIG. 2 is a top plan view of the base of the game console, shown separately for clarity;

FIG. 3 is a bottom plan view of FIG. 2;

FIG. 4 is a left side elevational view of FIG. 2;

FIG. 5 is a right side elevational view of FIG. 2;

FIG. 6 is a rear elevational view of FIG. 2;

FIG. 7 is a front elevational view of FIG. 2;

FIG. 8 is a front elevational view of one of the controllers for the game console, shown separately for clarity;

FIG. 9 is a rear elevational view of FIG. 8;

FIG. 10 is a left side elevational view of FIG. 8;

FIG. 11 is a right side elevational view of FIG. 8;

FIG. 12 is a top plan view of FIG. 8;

FIG. 13 is a bottom plan view of FIG. 8;

FIG. 14 is a front elevational view of another controller of the game console, shown separately for clarity;

FIG. 15 is a rear elevational view of FIG. 14;

FIG. 16 is a left side elevational view of FIG. 14;

FIG. 17 is a right side elevational view of FIG. 14;

FIG. 18 is a top plan view of FIG. 14; and,

FIG. 19 is a bottom plan view of FIG. 14.
